J. M. GREGORY

DISPLAY RECEPTACLE

Filed May 5, 1925

Inventor

John M. Gregory

By Harry D. Wallace
Attorney

UNITED STATES PATENT OFFICE.

JOHN M. GREGORY, OF SKANEATELES, NEW YORK, ASSIGNEE TO THE CAMPFIRE COMPANY, OF MILWAUKEE, WISCONSIN, A CORPORATION OF WISCONSIN.

DISPLAY RECEPTACLE.

Application filed May 5, 1925. Serial No. 28,223.

To all whom it may concern:

Be it known that I, JOHN M. GREGORY, a citizen of the United States, residing at Skaneateles, in the county of Onondaga and State of New York, have invented certain new and useful Improvements in Display Receptacles, of which the following is a specification.

This invention relates to a receptacle, designed for use by storekeepers, and the like, for storing as well as for displaying various goods, such as candies, nuts, fruit, and other articles, and has for its object to provide novel, simple and convenient means for utilizing the receptacle that contains the goods in bulk, for displaying a portion of the contents, and at the same time protecting the goods from the atmosphere, dust and dirt.

A further object is to provide a relatively shallow tray which may be hinged to an ordinary telescoping cover, such as commonly employed for closing receptacles of this class, the cover being formed with an opening in its top, in which the tray may be sunk, and the mouth of the tray being closed by a transparent disc or plate, which may be readily and quickly removed for affording access to the interior of the tray, while the tray and disc may be swung on its hinge away from the cover, for permitting access to the goods stored in the body of the receptacle. And a further object is to improve and simplify the construction arrangement and operation of display receptacles generally.

The various features and parts of the invention will be understood from the detailed description which follows, and by reference to the accompanying drawing, in which—

Figure 1 is a top plan view of the complete receptacle, to which my improvement is applied, a portion of the transparent disc being broken away for disclosing the goods in the tray. Fig. 2 is a broken elevation, and partial central vertical section, the latter being taken on line 2—2 of Fig. 1. And Fig. 3 is a modified view of the display tray.

In the drawing, 2 represents the body of an ordinary open top cylindrical can or box, having the usual circumferential rib 2', upon which rests a metallic band or hoop 3, corresponding to the usual depending flange of an ordinary telescoping can cover. The top of the hoop 3 preferably terminates in the same plane as the open circular top of the can, and may be snugly fitted to the can, or it

may be somewhat loose, and held in place by gravity. 4 represents generally my improved display device, which comprises a tray of any suitable depth, and preferably having a closed bottom 4' and a normally open top 4", the latter being shown formed with an overhanging folded circular flange 4", for stiffening the top. The vertical walls of the tray are preferably tapered for narrowing the bottom, whereby the tray may be readily and freely inserted in and removed from the mouth of the can. The contraction of the bottom 4' furthermore tends to hold any goods that may be disposed in the pan in the proper position for displaying the same. At one side, hereinafter referred to as the rear side, the flange 4" is fitted with spaced hinge-loops, as 5, the said loops having a single leaf 5', which may be rigidly secured to the underside of the flange, as by soldering, in a well-known manner. The hoop 3 is also fitted with a similar hinge-loop 3', whose sole leaf 3", may also be soldered to the hoop. A pin 5" driven through the several loops, completes the hinge, by which the tray 4 may be swung towards and away from the can 2, as shown by dotted and full lines in Fig. 2. Adjacent the hinge, I provide a guard or stop 6, which when swung downwardly engages the rear side of the hoop 3, for arresting the opening movement of the tray. At the opposite sides of the hinge, and at corresponding angles from the center of the tray, the flange 4" is fitted with clips or guards 7, which may be soldered or otherwise secured to the flange, the overhanging portions of said clips being spaced from the top face of the flange sufficiently to receive a disc or plate of glass or other transparent material, as 8, by which the open top of the tray is closed. The clips 7 are disposed in a manner to permit the insertion of the glass from the front side of the can, and the clips are so positioned and spaced that the glass 8 may be removed and replaced, without requiring any loosening or disturbing of the clips, by simply elevating and lowering the forward edge of the glass, as shown by dotted lines in Fig. 2. The tray 4 may be lifted and swung on its hinge, by means of a handle or finger-grip 9, which is preferably rigidly soldered or otherwise fastened to the edge of the flange 4" diametrically opposite the hinge. This handle is formed with a substantially vertical shoulder 10

105

110

9', directly opposite the front edge of the glass 8 when the latter is in the closed position (see Fig. 2), the said shoulder serving to prevent accidental shifting of the glass 5 away from the hinge. Immediately above the shoulder 9' the handle 9 curves upwardly and outwardly, and this peculiar formation permits the front edge of the glass to be raised, as well as moved bodily, in the direction 10 for withdrawing its rear edge from beneath the clips 7. The glass 8 must be removed, as described, in order to gain access to the interior of the tray 4. The goods, as 15, in the present case, are intended particularly to represent marshmallows or caramels, which are usually mounted upon discs or sheets of cardboard, as 10', upon which the candy as a rule remains during shipment and storage, or until sold. According to the 20 present showing, the main receptacle 2 is substantially filled with a number of stacked layers of the goods 10 (see dotted lines in Fig. 2), one of the layers having been removed from the can and placed in the tray 25 4, for display purposes, while the disc 10' is shown resting upon the bottom 4'. The platters or discs 10' are shown slightly smaller than the diameter of the bottom 4', and therefore tend to hold the discs and their 30 loads of goods substantially concentric to the transparent plate 8, as shown in Fig. 1.

Obviously, instead of the construction shown in Fig. 2, the bottom may be formed with a relatively large opening 4°, 35 which is surrounded by an annular ledge 4', as shown in Fig. 3. In this modified view the disc 10', that supports the goods, may be supported directly by the ledge 4°. This latter construction and arrangement reduces 40 the amount of metal, and lessens the weight of the tray.

Having thus described my invention, what I claim, is—

1. The combination with an open top 45 receptacle, and a hoop surrounding said top, of a display tray closing the top of the receptacle comprising a circular flange adapted to overlap and rest upon the top margin of the receptacle, and a depending drawn portion 50 that sinks concentrically into the receptacle,

a transparent disc for closing the mouth of the tray imposed upon said flange, clips mounted on the opposite sides of said flange for loosely holding the disc in place, means for hinging the edge of said flange between said clips to said hoop, and a handle supported by the edge of said flange opposite the hinge and preventing the disc from shifting away from said clips.

2. The combination with an open top receptacle, of a hoop telescoping the said top, a display device closing the top end of said hoop comprising an annular flange of greater diameter than the hoop, which overlaps the hoop, and a shallow pan-like portion that 65 extends into the open top of the receptacle, the said flange being hinged to the hoop, and having a handle disposed diametrically opposite the hinge, for swinging the tray towards and away from the receptacle, a 70 transparent disc overlaying the said flange and being held from accidental displacement by said handle, and a plurality of clips carried by said flange for normally holding the disc parallel to the flange.

3. The combination with an open top receptacle and a hoop surrounding said top, of a display cover comprising a drawn sheet-metal body having a closed bottom, the free edge of said cover being folded upon itself 80 to form a circular reinforcing flange that overlaps the top margins of the receptacle and said hoop, means for hinging one side of the cover to said hoop, a stop mounted on said flange adjacent the hinge, similar clips 85 mounted on said flange at corresponding angles from the center of the cover, a transparent disc held in place by said clips and said flange, a handle for raising and lowering the cover, said handle being mounted on 90 the forward edge of the flange, and a portion of said handle forming an abutment for preventing accidental shifting and release of the disc, and said handle above said abutment being curved away from the cover for 95 permitting the disc to be withdrawn from said clips.

In testimony whereof I affix my signature.

JOHN M. GREGORY.
